UNITED STATES PATENT OFFICE.

JOHN CAMPBELL WHEELON, OF GARLAND, UTAH.

DAM.

1,008,760.

Specification of Letters Patent. Patented Nov. 14, 1911.

Application filed September 30, 1910. Serial No. 584,668.

To all whom it may concern:

Be it known that I, JOHN C. WHEELON, a citizen of the United States, and a resident of Garland, in the county of Boxelder and State of Utah, have invented a new and Improved Dam, of which the following is a full, clear, and exact description.

The invention relates to hydraulic engineering, and its object is to provide a new and improved dam having a collapsible crest, which can be raised or lowered at will to permit flood waters to be safely discharged over the dam with the utmost safety to the dam and all the head works and controlling works connected with the water way.

The invention consists of novel features and parts and combinations of the same, which will be more fully described herein-
after and then pointed out in the claims.

A practical embodiment of the invention is represented in the accompanying drawings, forming a part of this specification, in which similar characters of reference indicate corresponding parts in all the views.

Figure 1 is a plan view of the improvement; Fig. 2 is a sectional side elevation of the same on the line 2—2 of Fig. 1; Fig. 3 is a front face view of the same, parts being broken out; Fig. 4 is a side elevation of the improvement and showing means for collapsing the crest of the dam; Fig. 5 is an enlarged transverse section of the improvement on the line 5—5 of Fig. 1, and showing more particularly the hinged connection between a frame and a race-way section, and Fig. 6 is a sectional side elevation of a modified form of the connections between the stanchions and runway sections.

The base or body of the dam is built across the water-way, of solid masonry, timber or other suitable material in the usual manner, and on the top of this base A is held a collapsible crest B made in sections, each forming a complete unit of the collapsible crest, the sections being collapsible independent one of the other, and the members of the sections being arranged to allow of storing the same on the top of the base A when the crest is collapsed.

The detail construction of the collapsible crest B is as follows: On the top of the base

A are arranged the girders C and D, of which the girder C is located on the upstream side thereof, the said girders extending the entire length of the base A and being firmly secured thereto. Between the girders C and D are arranged the supports E and E' bolted or otherwise fastened to the top of the base A, and carrying yokes F and F', on which are pivoted the side members G' and G² of supporting frames G, made in an inverted U shape, that is, having the side members G' and G² connected with each other at the top by a cross bar G³. By the arrangement described the supporting frames G are pivoted between the stringers C and D and hence can be swung into the space or pocket formed between the stringers C and D at the time the crest is collapsed, as hereinafter more fully described. A brace G⁴ serves to reinforce each supporting frame G. The supporting frames G are adapted to support a run-way H, made in sections, of sheet metal, each section being provided at its sides with angle irons, forming rails for the wheels I' of a wheeled derrick I to travel on, and on one end of each run-way section are arranged rings H² through which extends a corresponding cross beam G³ of a frame, so that this run-way section is hinged or pivoted on the corresponding supporting frame G. The free end of this run-way section is adapted to rest on brackets G⁵, bolted or otherwise fastened on the cross bar G³ of the next following supporting frames G, so that each run-way section is supported at its ends by adjacent supporting frames G (see Fig. 5).

On the cross bars G³ of the supporting frames G and near the up-stream side thereof, are arranged angular bars J for supporting girders K made of angle iron, and supporting one, two or more stanchions L, pivotally connected near their upper ends at L' to the girder K, as indicated in the drawings, to allow of swinging or of folding the stanchions L onto the corresponding girder K. As indicated in Fig. 3, two such stanchions L are employed for each crest section, and the two stanchions thus used are placed proper distances apart and spaced correspondingly from the side bars G² of the adjacent supporting frames G, as will be read-

ily understood by reference to Fig. 3. The stanchions L are of angle iron and the side bars G² of the supporting frames G are similarly shaped, so that the said side bars 5 and the stanchions L form supports for crest face plates N resting with their lower ends in a longitudinally extending groove G' formed on the top of the up-stream stringer C. Thus for each crest section two stanchions L are employed, which, in connection with the adjacent side members G² of the supporting frames G, support three crest face plates N. Each of the crest face plates N is adapted to be hung loosely on a stud O 10 held on the girder K, to prevent the crest face plate from accidentally shifting. Each of the crest face plates N is preferably provided at its front face with a longitudinally-extending reinforcing angle iron N'. Each 15 crest plate N is provided near its upper corners with apertures N², for engagement by a suitable tackle or other means employed for removing the crest face plates when it is desired to collapse the crest or when it is 20 desired to erect the crest and replace the crest face plates N. The lower ends of the stanchions L are supported on the stringer C when the crest is erected, so that the crest is sufficiently strong to withstand the pressure 25 of the water.

Instead of the girder K and supporting bars J, use may be made of the construction shown in Fig. 6, in which a bracket J' is riveted to the runway H and is provided 30 with a bearing J² for a pin K' to turn in, and which pin K' is pivoted at K² to a bracket K³ on the stanchion L. Thus, when the parts are collapsed, the stanchions are 35 free to swing into folded position, the 40 stanchions moving with the runways when folded or extended.

The adjacent sections of the crest are interlocked with each other by suitable means, preferably a chain P, secured at one end to 45 one end of the runway section H and removably attached at the other end of an adjacent section of the runway H by the use of a bight or similar means P'. The chain P is of considerable length, for a purpose to 50 be presently described, and when the bent and runway forming the crest are in upright position, a short length of chain is used as a guy to hold the runway from slipping off the brackets, the said short length 55 being engaged in a bight and the remainder of the chain is coiled up on the runway. This chain P is adapted to be engaged by the hook Q' of a tackle Q, having its windlass Q² mounted on a mast I² mounted to 60 turn on the derrick I, previously mentioned, and adapted to travel on the rails H' of the runway H. The tackle Q is supported on a yard-arm I³, attached to the upper end of the mast I², as plainly indicated in Fig. 4.

65 The stringer D at the down-stream side

of the dam is provided at intervals with bottom recesses or openings D' for the passage of sand and other flotsam at the time the crest is collapsed and stored in the pocket formed on top of the base A between the 70 stringers C and D.

In lowering the crest of the dam use is made of the derrick I, run along the rails H' of the run-way H, the said derrick I being locked in position on any one of the sections 75 by a locking device R (see Fig. 4). The locking device R is preferably in the shape of a screw rod clamp adapted to engage the run-way H and mounted on the platform of the derrick I, as shown in Fig. 4, the handled nut R' of the screw rod clamp R serving to draw the latter tight, with a view to securely hold the derrick I temporarily immovable on the corresponding section of the run-way H. A fork or other like tool is attached to the tackle Q, and this fork is engaged with the apertures N² of one of the crest face plates and then the windlass Q² is actuated so that the crest plate is lifted 80 out of place, after which the mast I² is 85 swung around and with it the crest plate, to permit of depositing or storing the same on top of the base A in the rear of the section on which the derrick I is fastened at the time. This operation is repeated for 90

the several crest face plates N of the sections to be collapsed, and then the girder K is raised by the use of the tackle Q and also deposited or stored in the pocket on top of the crest face plates already placed in storage in the pocket. The stanchions L are 100 folded upon the girder K when the latter is raised, as above explained, so that the stanchions and the girder K take up comparatively little space. The derrick I is 105 now unlocked and backed onto the next preceding section and locked in place thereon by the locking device R, after which the chain P is raised with its loose end on the run-way section on which the derrick I is 110 fastened at the time, and then the terminal of this chain is fastened in place on this run-way section and the chain P is then engaged with the hook Q' (see Fig. 4), and the windlass Q² is actuated, so that the run-way section is lifted off its supporting brackets G⁵, and then the run-way section with the forward supporting frame G is swung downward, to fold into the pocket on top of the base A and upon the crest face plates 115 N and the girder K, which belong to the section next ahead.

In raising the crest, the slack chain P, having one end attached to a section already standing and the other end attached to a 120 stored section of the run-way H, is grappled by the grapple hook Q' of the derrick tackle Q, and by manipulating the windlass Q² the stored run-way section H and with it 125 its supporting frame G is swung up into position.

sition and the free end of the run-way section is placed on the supporting brackets G⁵, after which the chain P is dropped into the bight P' on the runway section already 5 in place and on which the derrick I is temporarily locked in place, so as to lock the runway section just raised in place. The girder K is next picked up from the pocket and set in place on the runway section, after 10 which the stanchions L are swung downward in engagement with the stringer C, and then the several crest plates N are lifted consecutively from the pocket by the use of the tackle Q, and placed in position on the 15 stanchions L and the side arms G², to complete the section. When this has been done the derrick I is unlocked and moved onto the section just erected, after which the above-described operation is repeated until all the 20 sections are erected and the crest is complete across the entire length of the dam.

It is understood that the height of the crest corresponds to the difference between the normal water level and the flood level of 25 the waters in the stream above the dam. When the crest is collapsed and its members are stored on top of the base A between the stringers C and D, then a spillway is formed extending the entire length of the dam, so 30 as to render the headworks and canals of the waterway perfectly safe against damage by flood. When the crest is erected it forms a weir to store the water in other than flood times.

35 When the crest is collapsed immediately previous to the beginning of the flood time, then the surplus water, brush, logs and all flotsam of flood conditions pass over a smooth crest uninterruptedly and without 40 clogging up or impeding the flow of the water. The top of the dam when the crest is collapsed is as much lower than the original height of the dam as the difference between the normal and flood water levels. 45 As the flood subsides, the crest sections can be raised rapidly as the occasion may require, to prevent the release of too much of the necessary impounded waters.

The collapsible crest can be applied to any 50 wooden, crib or masonry dam already in use by cutting down the structure and installing the collapsible crest thereon. In the case of wooden dams which have shown signs of 55 weakness by age or decay, the installation of the collapsible dam will relieve the strain caused by a heavy flood and thus extend the life of the structure many years, and when a new dam is required the collapsible crest is still in condition to be successfully installed in the construction of the new dam 60 without loss.

The collapsible metallic dam is especially 65 desirable in the construction of new dams, as the factor of safety or strength can be reduced materially owing to the unknown

weight against the dam due to the excessive flood heights, and consequently a much lighter cross section in the main structure can be used as the floods are at all times under perfect control and the new dam can 70 be built with the collapsible superstructure better than without it.

It is expressly understood that the collapsible dam has two main functions, that is, to form a weir and a spill-way, by which 75 a uniform head of water surface of any height may be constantly maintained.

Having thus described my invention, I claim as new and desire to secure by Letters Patent:

1. A dam provided with a dam base, stringers on the top of the body at the up-stream and down-stream side thereof, supporting frames mounted to swing on the said base in the direction of the length of 85 the base, a sectional girder held on the top of the said supporting frames, stanchions on the said stringer and adapted to rest on the up-stream stringer, and crest face plates removably supported on the said stanchions. 90

2. A dam having frames hinged to swing in the direction of the dam, and a run-way made in sections each hinged at one end to one frame and resting at its other end on the next adjacent frame, the adjacent ends 95 of the run-way sections being locked together.

3. A dam having frames hinged to swing in the direction of the dam, a run-way made in sections each hinged at one end to one frame and resting at its other end on the next adjacent frame, and a chain for connecting the adjacent ends of the run-way sections with each other. 100

4. A dam having frames hinged to swing in the direction of the dam, a run-way made 105 in sections each hinged at one end to one frame and resting at its other end on the next adjacent frame, a chain for connecting the adjacent ends of the run-way sections with each other, and a car having a derrick and traveling on the said runway, the derrick having means for engaging the said chain. 110

5. A dam having frames hinged to swing in the direction of the dam, a run-way made 115 in sections each hinged at one end to one frame and resting at its other end on the next adjacent frame, the adjacent ends of the run-way sections being locked together, a sectional girder removably held on the 120 said frames, stanchions pivoted on the said girder, and crest face plates removably supported on the said stanchions.

6. A dam having frames hinged to swing in the direction of the dam, a run-way made 125 in sections each hinged at one end to one frame and resting at the other end on the next adjacent frame, the adjacent ends of the run-way sections being locked together, a sectional girder removably held on the 130

said frame, stanchions pivoted on the said girder, crest face plates removably supported on the said stanchions, and a stringer on the up-stream side of the dam and having a 5 groove for the reception of the lower ends of the stanchions and face plates.

7. A dam having frames hinged to swing in the direction of the dam, a run-way made in sections each hinged at one end to one 10 frame and resting at the other end on the next adjacent frame, the adjacent ends of the run-way sections being locked together, a sectional girder removably held on the said frames, stanchions pivoted on the said girder, crest face plates removably supported 15 on the said stanchions, a stringer on the up-stream side of the dam and having a groove for the reception of the lower ends of the stanchions and face plates, and a 20 stringer on the down-stream side of the dam, between which stringers the said frames are hinged to allow the frames to fold between the stringers.

8. A dam having frames hinged to swing 25 in the direction of the dam, a run-way made in sections each hinged at one end to one frame and resting at the other end on the next adjacent frame, the adjacent ends of the run-way sections being locked together, 30 a sectional girder removably held on the said frames, stanchions pivoted on the said girder, crest face plates removably supported on the said stanchions, a stringer on the up-stream side of the dam and having a 35 groove for the reception of the lower ends of the stanchions and face plates, and a stringer on the down-stream side of the dam, between which stringers the said frames are hinged to allow the frames to 40 fold between the stringers, the said girder, stanchions and face plates being stored between the stringers when the dam is collapsed.

9. A collapsible dam made in sections, 45 each comprising a swing frame, a run-way section, a girder, stanchions and crest face plates.

10. A collapsible dam having hinged frames, run-way sections, each hinged at one 50 end on one frame and adapted to rest with its free end on the next frame, a girder removably held on the said frames and provided with pivoted stanchions, and crest face plates, resting against the said stanchions.

55 11. A collapsible dam having hinged frames, runway sections each hinged at one end on one frame and adapted to rest with its free end on the next frame, a wheeled derrick mounted to travel on the said runway, and a chain attached to one end of a runway section and adapted to engage the end of the adjacent runway section, the chain being adapted to be engaged by the 60 said derrick.

65 12. A collapsible dam having hinged

frames, runway sections each hinged at one end on one frame and adapted to rest with its free end on the next frame, a wheeled derrick mounted to travel on the said runway, a chain attached to one end of a runway section and adapted to engage the end of the adjacent runway section, the chain being adapted to be engaged by the said derrick, and means for temporarily locking the derrick in place on any one of the runway 75 sections.

70 13. A dam having a collapsible crest consisting of interlocking sections forming a weir when erected, and a spill way when collapsed, each section comprising an inclined 80 crest plate for the up stream side of the dam, and a runway supported at the upper edge of the crest plates, a frame for each section foldable longitudinally of the dam for supporting the crest plate and runway, and a 85 chain connecting the sections, the said chain being fixed to one section and detachably connected with the other.

14. A dam having a collapsible crest consisting of interlocking sections forming a 90 weir when erected, and a spill way when collapsed, each section comprising an inclined crest plate for the up stream side of the dam and a runway section supported at approximately the level of the upper edge 95 of the crest plate, a frame for each section foldable longitudinally of the dam for supporting the crest plate and the runway, a flexible strand connecting each adjacent pair of sections, said strand being rigidly connected with the runway of one section and having a detachable connection with the runway of the adjacent section, and a stringer near each side of the dam and between which the foldable frames are hinged 100 to fold.

15. A dam having a collapsible crest consisting of interlocking sections forming a 110 weir when erected, and a spill way when collapsed, each section comprising an inclined crest plate for the up stream side of the dam and a runway section supported at approximately the level of the upper edge of the crest plate, a frame for each section foldable longitudinally of the dam for supporting the crest plate and the runway, a flexible strand connecting each adjacent pair of sections, said strand being rigidly connected with the runway of one section and having a detachable connection with the runway 115 of the adjacent section.

16. A dam having a collapsible crest consisting of interlocking sections forming a 125 weir when erected and a spill way when collapsed, each section consisting of an inclined crest for the up stream side of the dam and a runway supported at the upper edge of the crest plate, a frame for each section foldable longitudinally of the dam for supporting the crest plate and the runway 130

way, a detachable flexible connection between the adjacent sections, each foldable frame having a supporting bar inclining upwardly from the frame toward the crest 5 plate, and an angle plate girder having one face engaging the supporting bars, the crest plate resting against the other side.

In testimony whereof I have signed my name to this specification in the presence of two subscribing witnesses.

JOHN CAMPBELL WHEELON.
